UNITED STATES PATENT OFFICE.

JOHN FENTON, OF COLUMBUS, OHIO, ASSIGNOR TO THE SELBY SHOE CO., OF PORTSMOUTH, OHIO.

HEEL SUPPORT.

Application filed October 19, 1925. Serial No. 63,436.

Nature has decreed that man shall walk upright on a flat surface and shall maintain a proper center of gravity to insure equilibrium or poise. I have found that this center of gravity extends perpendicularly from the point at the front end of the heel bone to the center of the head at a point between the ears. When we stand upright upon normal feet, without shoes and in a natural position, we rest on two weight bearing points, the ball and heel, and there is perfect comfort to the body. However, when we elevate only the posterior part of the feet by wearing shoes having heels, we distort the correct poise of the body, the knees are bent forwardly to maintain equilibrium, and an undue strain is placed upon the muscles of the feet, legs or back. These muscles weaken and fail to supply the necessary strength. Thus, the bony structure of the foot is allowed to extend to an unnatural length, resulting in numerous forms of foot, knee and quite a number of hip and pelvic troubles. These troubles in many cases can be prevented by the wearing of shoes with heels that will restore to the body the equilibrium lost by the addition of elevated heels.

It is the primary object of my invention to provide a shoe having an improved construction which will enable a normal foot to function correctly when walking and retain its natural poise, and not only prevent any troubles caused by incorrect poise of the body, but in addition, will correct many troubles now existing which are caused by the wearing of shoes with various heights of heels, by restoring the body to the correct center of gravity, thereby reducing the strain on the muscles, enabling the ligaments to remain at or contract to their normal lengths, and restoring the foot bones to their normal relative positions.

With the foregoing in view, the invention resides in the novel subject matter herein-after described and claimed, the description being supplemented by the accompanying drawings.

Figure 1 is a perspective view of a last prepared for shaping of the heel-supporting portion of the shoe.

Figure 2 is a perspective view showing one step in the production of the heel portion of a shoe.

Figure 3 is a view similar to Fig. 2 but showing the completed heel portion.

Figure 4 is a longitudinal sectional view through a complete shoe illustrating the improved heel-supporting means in elevation.

Figure 5 is a perspective view of the heel-supporting means separate from the shoe.

Figure 6 is a transverse sectional view on line 6—6 of Fig. 5.

Figures 7 and 8 are diagrams showing respectively the incorrect and correct poise of the body.

A lady's shoe has been shown having a comparatively high heel H, and to prevent any of the troubles above referred to or to correct such troubles if they exist, the sole structure S of the shoe is specially made, according to my invention. This sole structure includes the usual inner sole I, and I provide the heel portion of this inner sole with laterally spaced longitudinally disposed abutments 10 and 11, between which lies the portion of the heel directly underlying the heel bone B. The abutments 10 and 11 are offset longitudinally with respect to each other and their heel-engaging surfaces converge downwardly and are longitudinally curved, so that the front portions of said abutments diverge forwardly and the rear portions thereof similarly diverge in a rearward direction. The abutment 11 is adapted to engage the outer rear portion of the heel and the abutment 10 engages the inner forward portion of the heel. In this connection, it may be stated that the shoe herein disclosed is for the left foot and the method disclosed is for the construction of this left shoe, it being understood that the relation of parts is reversed for the right shoe.

The heel portion of the sole is substantially flat, with the exception of the abutments 10 and 11 and by relating these abutments and shaping them in the manner disclosed, a somewhat oblique, flat-bottomed channel 12 is formed for the reception of the user's heel, and the heel is so snugly received in this channel, between the abutments 10 and 11, that correct poise to the body is insured, as well as preventing any of the troubles above enumerated, and serving to correct such troubles should they exist, before wearing of the improved shoe.

In the manufacture of the shoe, I make

use of an ordinary wooden last L. I cut away longitudinal portions of this last at its lower side, along the margins of its heel portion, forming inner and outer recesses 13 and 14 respectively, which recesses are longitudinally offset with respect to each other, as clearly shown in Fig. 1. I then secure a piece of leather or other desired material 15 upon the last, such material covering the heel portion of said last and the contiguous shank portion, and I skive the front end of this piece of material to a feather edge. At 16 and 17, I depress the material into the recesses 13 and 14 respectively, as clearly shown in Fig. 2. Then, appropriate fillers 18 and 19, formed of layers of leather or other desired material, or formed each in one piece if desired, are secured in the depressions formed in the piece of material 15, by depression of the latter into the recesses 13 and 14. In the present showing, the fillers 18 and 19 are formed of a plurality of plies of leather or the like having their edge portions suitably skived, said plies being secured in the recesses of the piece of material 15, by tacks 20. After securing of the fillers 18 and 19, the lower surface of the unit formed by them and the piece of material 15, is given a substantially flat form as indicated by the shading in Fig. 3, although the forward tip 21 of this unit, curves to some extent along the shank portion of the last.

After performing the operations above described, the inner sole may be secured upon the unit 15—18—19—21, and after this, the shoe may be completed in the usual manner. In the completed shoe, the piece of material 15 constitutes the heel-engaging surface at the rear portion of said shoe, and the bowed portions 16 and 17, together with the fillers 18 and 19, form the abutments 10 and 11. Preferably, a lining (not shown) is provided over the entire surface of the improved sole, but may be omitted if desired.

While the method steps above described are preferably followed, it will be understood that other methods could be used for the production of the invention. Moreover, while the heel supporting unit disclosed in Fig. 5 is preferably built into the shoe as described, it may if desired be manufactured as a separate article or insert, to be secured in the ordinary shoe. In either case, the heel will be effectively and comfortably supported and the body will thus be maintained in true poise. In this connection, it may be stated that Fig. 8 discloses in a diagrammatic manner, the true poise of the human body when no shoes are worn, whereas Fig.

7 illustrates the manner in which the body is thrown out of equilibrium by elevation of the heel, when shoes are worn having high heels. The use of my invention overcomes the condition graphically depicted in Fig. 7, in which the knees K and hip bones HB are considerably forward from the center of gravity L', instead of being on such center, as they should.

Excellent results are obtainable from the details disclosed and they are therefore preferably followed. However, within the scope of the invention as claimed, variations may of course be made.

I claim:—

1. An inner sole member provided on the upper side of its heel portion with a pair of laterally spaced longitudinally disposed abutments between which lies the portion of the wearer's heel directly underlying the heel bone, said abutments being longitudinally offset from each other, positioning the outer abutment to engage the outer rear portion of the heel and disposing the inner abutment to engage the inner front portion of the heel.

2. An inner sole member provided on the upper side of its heel portion with a pair of laterally spaced longitudinally disposed abutments between which lies the portion of the wearer's heel directly underlying the heel bone, said abutments being longitudinally offset from each other, positioning the outer abutment to engage the outer rear portion of the heel and disposing the inner abutment to engage the inner front portion of the heel, said abutments having longitudinally curved heel-engaging surfaces which converge downwardly but diverge from their intermediate portions to their front and rear ends.

3. An inner sole member provided on the upper side of its heel portion with a pair of laterally spaced longitudinally disposed abutments between which lies the portion of the wearer's heel directly underlying the heel bone, said abutments being longitudinally offset from each other, positioning the outer abutment to engage the outer rear portion of the heel and disposing the inner abutment to engage the inner front portion of the heel, said abutments having longitudinally curved heel-engaging surfaces which converge downwardly but diverge from their intermediate portions to their front and rear ends, said heel portion of the sole being substantially flat with the exception of said abutments.

In testimony whereof I have hereunto affixed my signature.

JOHN FENTON.
